TOE REST

Charles K. Woodman, Beverly, Mass., assignor to
United Shoe Machinery Corporation, Flemington, N. J., a corporation of New Jersey

Application April 16, 1947, Serial No. 741,749

8 Claims. (Cl. 12—127)

1

This invention relates to machines for use in the manufacture of shoes and more particularly to shoe-supporting means or toe rests. The invention is herein illustrated as applied to means for supporting the forepart of a shoe against pressure applied to its bottom in the operation of cement-sole-attaching. It is to be understood, however, that in its more general aspects, the invention is not limited to means for operating on that particular portion of a shoe nor to machines for pressing soles on shoe bottoms.

In some machines for operating on shoes, substantial pressure is applied to the top of the forepart of the shoe in order to support the shoe in proper position or to cooperate with means for applying pressure to its bottom. In cement sole-attaching machines, for example, heavy pressure is applied for a considerable time to the forepart of the shoe while the shoe and sole are being pressed tightly together to allow the cement between them to set. The commonly used felt or other cushion with which toe rests are provided does not evenly distribute the applied pressure over the area pressed on, with the result that excessive pressure is applied to some part of the area pressed on and marking of the upper occurs. Such marks are difficult to remove. Moreover, the action of such a cushion is progressive, that is, the more pressure the greater the yield without any definite limit.

Objects of this invention are to provide means for evenly distributing the pressure over the whole area to which pressure is applied and then to sustain the pressure unyieldingly. Thus the danger of injury to the upper of the shoe is avoided and the position of the shoe is accurately maintained.

In the form illustrated, a casing having opposite parallel sides and a bottom perpendicular to the sides is provided in which, perpendicular to the bottom, is a multiplicity of elongate members or rods parallel to each other with their inner ends occupying an area equal to that of the bottom of the casing and with their outer end portions extending beyond the casing. Between the inner ends of the rods and the bottom of the casing is a mass of steel balls of a diameter which is small relatively to the end area of one of the rods.

The rods are preferably square in cross-section and are arranged in rows both longitudinally and laterally of the casing. In the bottom of the casing is a polished sheet of material harder than the material of the casing, such as hard steel, which prevents the balls from indenting or pit-

2

ting the bottom of the casing, as occurs when heavy pressure is applied to the rest. The polished surface of the sheet also facilitates movement of the balls when different portions of the mass are under unequal pressure. A flexible cover extends over the exposed ends of the rods and means other than the cover for holding the rods in the casing is provided so that the cover may be removed without danger of the rods and balls falling out of the casing, such holding means being arranged to permit the desired relative endwise movement of the rods.

These and other features of the invention will appear more fully from the following description when read in connection with the accompanying drawing and will be pointed out in the appended claims.

In the drawing,

Fig. 1 is a side elevation of a toe rest applying pressure to a shoe on an inflatable pad, the shoe and pad being in section and the cover of the rest being broken away;

Fig. 2 is an end elevation of the toe rest shown in Fig. 1;

Fig. 3 is a fragmentary sectional view on a plane indicated by the line III—III in Fig. 1;

Fig. 4 is a longitudinal sectional view taken in the plane indicated by the line IV—IV in Fig. 2; and

Fig. 5 is a fragmentary sectional view taken in a plane indicated by the line V—V of Fig. 4.

The toe rest of the present invention comprises a casing having a bottom wall 10 provided with a supporting stem 12, end walls 14, 16 and side walls 18, 20, the opposite walls being parallel to each other, and the end walls joining the side walls and the bottom at right angles. In the casing is a multiplicity of prismatic elongate members such as rods 22, preferably identical in cross-section. The outer end portions of the rods extend beyond the open side of the casing. The rods are in contiguous parallel relation and are arranged in rows both longitudinally and laterally of the casing. In the bottom of the casing is a hard steel plate 24, and between this and the inner ends of the rods 22 is a mass of steel balls 26. In a toe rest, for example, the rods may be $\frac{1}{8}$ inch square and of a convenient length and with rods of that size it is found that balls $\frac{1}{16}$ to $\frac{3}{32}$ of an inch in diameter give satisfactory results. The rods 22 being freely movable endwise within the limits of use, it will be apparent that pressure applied to the outer end of one of the rods will be transmitted through the mass of balls to the inner ends of all of the other rods which,

if their movement is unopposed, will move outwardly; that is, the rods will shift in or out until the pressure applied or sustained by their outer ends is substantially equal and hence the surface represented by their combined outer ends will conform to the contour of the surface pressed on or sustained by the rods. Thus, when the rods are pressed upon an irregular surface, their ends first conform to the contour of the surface and then rigidly sustain the pressure, the mass of balls becoming rigid after they have shifted so that there is substantially equal pressure on the inner ends of the rods.

A cover 28 of flexible material such as leather is attached by screws 30 to the side 20 of the casing, passed across the ends of the rods 22 and secured by screws 32 to the other side 18. The cover would prevent displacement of the rods from the casing but, since the covers have sometimes to be changed or removed, it is preferable to provide other means for retaining the rods in the casing. For this purpose the contiguous sides of each two rows of square rods extending across the casing beginning with the first two rows at one end are recessed at 34 to receive a round rod 36 which is passed through the wall 18 of the casing and between the square rods 22 in the recesses 34 and enters a hole in the opposite wall 20 of the casing. The recesses 34 permit limited free longitudinal movement of the rods 22 relatively to each other and to the casing but prevent the rods 22 from falling out when the cover is removed, the diameter of the rods being greater than the depth of one of the recesses. By this arrangement each round rod 36 holds two transverse rows of square rods 22 so that only half as many round rods need be provided as there are transverse rows of rods 22. The rods 36 are called "round" merely for identification, it being apparent that rods or bars of various cross-sections may be employed for the same purpose. It is also obvious that the rods 36 may extend lengthwise of the casing instead of crosswise, in which case a less number of rods would be required. It is desirable that the cover extend crosswise of the casing and, by arranging the rods 36 also crosswise, they may, as illustrated, be held in place by the same means which holds the cover. For this purpose the ends of the rods 36 are secured to a plate 40 which is held in place by the same screws 32 which hold one end of the cover 28. The ends of the rods 22 which engage the cover 28 are preferably somewhat rounded to prolong the wear of the cover. The stem 12 is for attaching the rest to a machine such as a cement sole-attaching machine, for example one having an inflatable pad, such a pad being indicated at 42 in Fig. 1.

It is, of course, immaterial whether the pad moves toward the shoe S or the toe rest moves toward the shoe or both. In either case the rods 22 shift endwise to conform to the contour of the area of the shoe engaged thereby and then become rigid for sustaining or applying further pressure. The balls, once equal pressure is applied to them by the rods, become immovable and, being incompressible, sustain the conformed rods rigidly without the necessity of additional locking means for the rods.

Having thus described my invention, what I claim as new and desire to secure by Letters Patent of the United States is:

1. In a shoe machine, a rest for engaging the forepart of a shoe upon a last, said rest comprising a casing having a bottom, a plurality of elongate members grouped in the casing in contigu-

ous parallel relation to one another with their outer ends exposed and relatively movable in that relation when the rest and shoe are pressed together to conform to the portion of the surface of the shoe which is engaged by the rest, a mass of steel balls between the inner ends of the elongate members and the bottom of the casing, a cover over the exposed ends of the elongate members, and means other than the cover for retaining said members in the casing.

2. A shoe rest for engaging the forepart of a shoe, comprising a casing having a bottom and a stem by which it may be attached to a shoe machine, a plurality of parallel rods in the casing, a mass of steel balls in the casing between the rods and the bottom of the casing, contiguous surfaces of the rods having recesses extending longitudinally of the rods, and means secured to the casing and passing freely through said recesses to prevent removal of the rods from the casing.

3. A shoe rest for engaging the forepart of a shoe, comprising a casing having a stem by which it may be attached to a shoe machine and a bottom, a plurality of parallel rods in the casing, a mass of steel balls in the casing between the rods and the bottom of the casing, contiguous surfaces of the rods having opposed recesses extending longitudinally of the rods, and means carried by the casing and passing freely through said recesses to prevent removal of the rods from the casing, said means being thicker transversely of the rods than the depth of the recesses.

4. A toe rest for shoe machines comprising a casing having a bottom, a plurality of square rods in the casing, a mass of steel balls in the casing between the rods and the bottom of the casing, said rods being arranged in contiguous parallel relation in a plurality of rows, the rods of each two rows beginning with the first two having in their contiguous faces opposed recesses extending lengthwise of the rods, and round rods held in the casing and extending through said recesses, the diameter of the rods being greater than the depth of the recesses.

5. In a shoe rest, a casing having a rectangular recess and a bottom perpendicular to the walls of the recess, square rods arranged in rows which extend transversely of the casing, said rods being disposed in contiguous parallel relation and being freely movable relatively to each other, each of said rods having a longitudinally extending recess in one face thereof, and means extending transversely of the rods in said recesses to prevent removal of the rods.

6. A shoe rest for engaging the forepart of a shoe, comprising a casing having a bottom and stem by which it may be attached to a shoe machine, a plurality of parallel rods in the casing, a mass of steel balls in the casing between the rods and the bottom of the casing, a hardened steel plate on the bottom of the casing in contact with the balls, contiguous surfaces of the rods having recesses extending longitudinally of the rods, and means secured to the casing and passing freely through said recesses to prevent removal of the rods from the casing.

7. In a shoe machine, a rest for engaging the forepart of a shoe upon a last, said rest comprising a casing having a bottom, a plurality of elongate members grouped in the casing in contiguous parallel relation to one another with their outer ends exposed and relatively movable in that relation when the rest and shoe are pressed together to conform to the portion of the

surface of the shoe which is engaged by the rest, contiguous faces of said members having opposed recesses, a mass of steel balls between the inner ends of said elongate members and the bottom of the casing, a cover over the exposed ends of the elongate members, pins extending transversely of the casing through said recesses, and common means for holding the cover and pins in position.

8. In a shoe rest, a casing having a rectangular recess and a bottom perpendicular to the walls of the recess, square rods arranged in rows which extend transversely of the casing, said rods being disposed in contiguous parallel relation and being freely movable relatively to each other, each two transverse rows having recesses in contiguous faces of the rods, means located between each two transverse rows of rods

10

15

to prevent removal of the rods, the recesses being of sufficient extent longitudinally of the rods to permit free limited longitudinal movement thereof to enable them to conform to the contour of the surface engaged thereby, and a mass of steel balls between the bottom of the casing and the ends of the rods.
